UNITED STATES PATENT OFFICE.

HANNS R. ANDERS AND MAXIMILIAN E. U. SCHOEDLER, OF PERTH AMBOY, NEW JERSEY, ASSIGNEES TO THE ROESSLER & HASSLACHER CHEMICAL COMPANY, OF NEW YORK, N. Y., A CORPORATION OF NEW YORK.

APPARATUS FOR BLEACHING.

1,173,474.

Specification of Letters Patent. Patented Feb. 29, 1916.

Original application filed March 30, 1912, Serial No. 687,426. Divided and this application filed April 4, 1913. Serial No. 758,826.

To all whom it may concern:

Be it known that we, HANNS R. ANDERS, a subject of the Emperor of Austria-Hungary, and MAXIMILIAN E. U. SCHOEDLER, a citizen of the United States of America, both residents of Perth Amboy, county of Middlesex, and State of New Jersey, have invented certain new and useful Improvements in Apparatus for Bleaching; and we do hereby declare the following to be a full, clear, and exact description of the invention, such as will enable others skilled in the art to which it appertains to make and use the same.

15 Our invention, which is a division of a pending application filed March 30, 1912, Serial #687,426, relates to new and useful improvements in apparatus for bleaching and more particularly to that class adapted 20 to be used in connection with bleaching agents, such as peroxids or persalts, in aqueous solution, from which agents oxygen may be easily obtained *in statu nascendi* in which state it has its greatest bleaching 25 effect.

The apparatus which we use for carrying out our method is also adapted to be used for dyeing, scouring, washing and rinsing purposes.

30 A further object of the invention is to provide means for a most economical utilization of the applied bleaching materials.

Other objects and advantages will herein-after be referred to and more particularly 35 pointed out in the specification and claims.

In the accompanying drawings, which illustrate one way of carrying out the invention, Figure 1 is a vertical sectional view on line A, A of Fig. 2, of an apparatus 40 in operative position; Fig. 2 is a top view of the same, parts being broken away or removed. Fig. 3 is a top view of the container of the bleaching vat removed from the vat and Fig. 4 is a vertical sectional 45 view of the same.

Similar numerals of reference indicate similar parts throughout the several views.

The apparatus comprises three main parts, a mixing vat 1, a pump 2 and a 50 bleaching vat 3. A system of pipes and other minor appurtenances complete the apparatus. In the drawings we have shown the mixing vat 1 as being cylindrical in

shape. It is preferably constructed of wood. We have shown the pump 2 as being of the 55 centrifugal type.

A lead coil 4 is suitably supported near the bottom of the mixing vat 1 by means of which the bleaching liquor may be heated with steam; the lead coil is preferably so 60 disposed that none of its windings crosses any other; furthermore the inlet and outlet (not shown) of the coil are preferably placed close to each other to allow easy handling. The cover 5 shown in Fig. 2 as 65 being partly broken away, is of sufficiently strong construction to carry a stirring apparatus, preferably in the form of a propeller 6, shown as mounted on a support 7 on a base 8 carried by cover 5. The propeller 6 70 is shown as inclined toward the bottom of the vat as is obvious from the drawing. An advantageous feature in connection with this form of stirring apparatus consists in the means for preventing even the least 75 traces of lubricating oil from entering the vat, as any drop of oil, falling from the lower arm of support 7, is caught in a groove 9 in base 8 directly below the support, and may be drained off.

The vat is emptied through a side outlet 10, and the bottom of the vat may if desired be slightly sloped toward this outlet to facilitate emptying. It has also been found advantageous to provide mixing vat 1 with a 85 perforated false bottom 11, preferably made of wood, suitably supported above the lead coil 4.

A pipe 12 extends from the lower portion of vat 1 and connects the same with bleaching vat 3 through the means hereinafter described; another pipe 13, preferably parallel to pipe 12, connects the upper parts of vat 1 and vat 3 as herein-after described. Pipes 12 and 13 are connected with pipe 14 and another pipe 15 extends from pipe 12, joining pipe 13, and forming a connection to vat 3 near its top where it branches off into two arms 16 and 17. Centrifugal pump 2 serves for moving the liquids within the apparatus 90 and is therefore connected with the above mentioned pipe system by means of short joint-pipes 18 and 19 respectively, and, by means of three-way stop cocks 20, 21, 22 and 23 and plain cocks 24 and 25, the path of the 95 liquid may be controlled very conveniently 100 105

to divert the same in various directions. By means of cock 23 the exhausted bleaching, dyeing, scouring, or washing liquor, etc., may be run off. The upper part of pipe 15 is provided with heating means, such as a coil 26, to control the temperature of the liquor while passing through the pipe system during the operation of the apparatus; this coil may be made from some material 10 suitable for the purpose of the machine, such as lead or copper.

The bleaching vat 3 comprises a wooden shell 27 and a container 28, the latter carrying the goods to be bleached. The wooden shell 27 is substantially in the form of an oblong box set up on one short end; for reasons which will be more fully explained below, it has a sloping bottom 29. A rectangular frame 30 rests on the sloping bottom 29 and around the inside opening is provided with a rim 31. An opening 32 in the bottom portion of vat 3, here shown as extending through one side of frame 30, serves as an inlet or outlet for the bleaching, dyeing, scouring, washing or rinsing liquor from the pipe system to the lower part of the bleaching vat or vice versa. Openings 33 and 33' are provided near the top of shell 27 at the front and rear sides 20 thereof to furnish a passage way for the liquor conducted through the branches 16 and 17 of pipe 15 to said vat 3, the liquor entering the vat at about the level of the top of container 28. The container 28 is 25 in the form of a wooden box of such dimensions as to slide loosely into the vat. Container 28 is held in position by the support afforded by frame 30 resting on the sloping bottom 29, container 28 resting over rim 31, as shown in Fig. 1. It is obvious that frame 30 in connection with rim 31 forms an opening over which container 28 is slipped thus forcing all the liquor from whatever side it may enter the bleaching vat 30 to pass through the container. The corner-posts 34, forming the main parts of the frame-work of the container 28, reach just up to the brim of the bleaching vat whereas the walls of the container reach only to 45 about six inches below said brim; suitable cross-pieces 35 are attached in any convenient manner to these corner posts to serve as a brace when the container is set in or taken out by means of a hoisting device. Two of 50 the opposite side-walls of the container are hinged to the container and when the latter is removed from the vat, said walls may swing like doors, but they do so in different directions as shown in Figs. 3 and 4, the 55 front wall for instance, being hinged at the upper short side and swinging upwardly and the rear wall being hinged at the right hand long side and swinging backwardly to the right. By means of this arrangement 60 the container may be emptied in a most con-

venient way. Ledges 36, (Figs. 2 and 4) are shown as extending downward on the inside of both the front and rear walls of the container, parallel to and at a suitable distance from the adjacent side wall of the 70 container, remote from the pump, to serve as a rest for the yarn sticks.

It is the usual custom at present, to charge the containers of bleaching apparatus by laying in the goods loosely in rows, but by 75 this method, the bleaching liquor readily forms channels through the goods, whereby the parts adjoining these channels are bleached more readily and thoroughly than those more remote from the same. The 80 goods are sometimes laid crosswise, to overcome, at least to some extent, this great defect in bleaching apparatus as used at the present time, but this method gives only a partial effect which must be made up by 85 continuing the bleaching process for a considerably longer time than when the goods are laid loosely in rows and if finally the goods are evenly bleached the goods adjoining the channels through the goods laid 90 crosswise are then very often seriously weakened in texture by over-oxidation, *i. e.* in case of an oxidizing bleaching process. All these defects are avoided by carrying out the bleaching process in our apparatus 95 which is adjusted to take the best advantage of the many subtle properties of the bleaching materials.

The operation of our apparatus is substantially as follows: The bleached liquid 100 is prepared in mixing vat 1 and in the meantime the bleaching vat 3 is made ready for its part in the process. The container 28 is hoisted out of the bleaching vat and while it is arranged to stand upright during the 105 bleaching process proper, the success of the latter is based on some advantages obtained only when the container is filled with the goods when lying in a horizontal position. The skeins of yarn are put on the yarn sticks 110 and there should preferably be as many skeins on each stick as is sufficient to fill the entire width of the container; precaution should be taken that the yarn neither hangs so loosely as to allow any interstices, nor 115 should it be too densely crowded so as to be submitted to even inconsiderable pressure. The yarn skeins fill the entire depth of the container when the same is in the horizontal position. It has furthermore 120 been found advantageous not to fill the yarn into the container as one solid body, but to intermittently separate a limited number of sticks carrying the yarn, by inserting perforated trellises 37, sliding or fitting 125 in grooves 38, formed on the side walls of the container, parallel to the bottom 39 of the container, which for the reason that the liquor must pass through this bottom should also be perforated: it is convenient there- 130

fore to use a like stationary trellis for the bottom of the container, said trellis being substantially at right angles to the side walls of the container. It is obvious that 5 it depends very much on the nature of the yarn as to how many sticks may be lined up before a trellis is put in to be followed again alternately by the same number of sticks and a trellis.

10 It has been ascertained that our apparatus furnishes the best results if about six sticks constitute one block and each block be separated by a trellis from the next following block. It is to be understood, of course, 15 that there cannot be a positively fixed rule about this, and although it is best to adhere to the practice pointed out above, as closely as possible, different kinds of yarn may be simultaneously treated requiring a deviation 20 from the general course.

In bleaching raw stock or small fabric in this apparatus a similar course is followed, inasmuch as first a trellis is set in parallel to the stationary bottom trellis, at such 25 a distance from the same as to form a compartment of such dimensions as to hold a block of goods of reasonable volume in view of the spirit of our invention; said block is then separated from the adjoining one by a 30 trellis, to be followed alternately by like layers of goods and trellises, until the container is properly charged with the goods. Yarn and raw stock or small fabric may simultaneously be bleached by this method 35 of using our apparatus as the situation may require.

Of all the goods which are subjected to the bleaching process, yarns constitute a very considerable part and it is in their 40 treatment where an essential feature of our new apparatus comes in. When the container is filled in the horizontal position the yarn hangs loosely down vertically and is held firmly by the trellises which are alternately inserted; but when the container is 45 then brought into the vertical position the yarn lies horizontally and is kept in this horizontal position by the trellises, all through the bleaching process.

50 In our apparatus we practically prevent the yarn from floating, contrary to all other bleaching apparatus, thereby avoiding the knotting of the threads of the skeins. Any one skilled in the art will see that these 55 latter advantages render our bleaching apparatus very much different from and far superior to any other heretofore known; there are, however, some further points which make for the better and greater success 60 of our apparatus.

If the container is charged with the goods while in a horizontal position as described and it is then turned into a vertical position, the entire container is most evenly filled.

65 The trellis laid on top of each block adjusts

and controls even the smallest pressure all over the upper surface and throughout the entire block of goods confined between two trellises and since the skeins are put in without exerting any force, it is obvious that the 70 resistance offered to the liquor by the goods is bound to be the same all over, and that therefore no chances for the formation of channels are given, thus evenly exposing all the goods to the bleaching action of the 75 liquor with the most desirable result.

Our new bleaching apparatus is especially adapted to carry out the process with the view of getting a final product conforming in every way with the demand for an even 80 quality of the finished goods. It is a great defect in the bleaching apparatus heretofore used, that the bleaching liquor passing through the apparatus does so exclusively in one direction. In constructing our apparatus special stress is laid on establishing a reliable arrangement to overcome this handicap, and by means of the pipe system with the various cocks connecting vats 1 and 3 as well as pump 2, the greatest facilities are 90 provided to permit or cause the liquor to move and pass in any possible direction whatsoever; it is obvious that the many possible changes permit the bringing about of a more effective saturation of the goods 95 by the liquor, resulting thereby in a more thorough and even bleach. This effect is furthermore greatly facilitated by inserting the coil 26 or other suitable heating system in the pipe 15, thus heating the liquor more 100 conveniently and suitably than may be done in the bleaching vat itself, where the heating action is more or less local, whereas, in passing through pipe 15 all the liquor may be heated to just such particular temperature as is necessary to moderately and gradually liberate the oxygen required for the 105 actual bleaching process.

The sloping bottom 29 of the bleaching vat serves very effectively to give the liquor 110 an upward trend when entering the vat at the bottom, or to serve as a guide when running off the liquor.

After the goods have been bleached as hereinabove described, the bleaching liquor 115 is drawn off and the goods are finished, without necessarily removing the same from the vat, by passing water or other suitable cleaning liquid through the vat by the means described, it being obvious that the 120 scouring, washing or rinsing steps may be most advantageously carried out in this manner.

It is also obvious without further description that our apparatus is equally well 125 adapted for the purpose of dyeing and we do not restrict ourselves to the use of the apparatus for the purposes described, further than the scope of the appended claims demand.

Where we use the word "bleaching" in the claims we mean to also include dyeing, cleaning, scouring, washing and rinsing as well.

5 We do not restrict ourselves to the exact details of the apparatus as above described further than the scope of the appended claims demand.

What we claim and desire to secure by 10 Letters Patent is:

1. In an apparatus for bleaching and the like a mixing vat, a bleaching vat, a pump and a pipe system consisting substantially of a pipe connecting the lower parts of both 15 the mixing and the bleaching vats, a pipe extending from the upper part of the mixing vat and terminating a short distance from the bleaching vat, a pipe communicating with both the aforesaid pipes adjacent 20 to the mixing vat, a pipe communicating with both the first mentioned pipes and the bleaching vat, and pipes between the pump and the pipe system.

2. In an apparatus for bleaching and the like a mixing vat, a bleaching vat, a pump, a pipe system, a three-way cock at each of the two upper pipe joints and at the lower pipe joint adjacent the mixing vat, a three-way cock in the lower horizontal pipe adjacent 25 the bleaching vat, a plain cock in the upper arm and one in the left arm of and adjacent the joint of the lower horizontal pipe and the vertical one extending from the same adjacent the bleaching vat and 30 finally connecting with the bleaching vat at its upper end, and pipes to connect the pump with the pipe-system.

3. In an apparatus for bleaching and the like a mixing vat, a bleaching vat, a pipe 40 system connecting said mixing and said bleaching vats, a pump with connection-pipes to join said pipe system, and means for heating the liquors in the upper part of the pipe connecting by its branches with the upper part of the bleaching vat.

4. In an apparatus for bleaching and the like the combination of a mixing vat, a bleaching vat, a pipe system connecting said mixing and said bleaching vats, a pump 50 with connections to said pipe system, and passage-ways for the liquors through both the front and rear walls of the bleaching vat near the brim of the bleaching vat.

5. In an apparatus for bleaching and the like the combination of a mixing vat, a bleaching vat, a pipe system connecting said mixing and said bleaching vats and a pump with connections to said pipe system, said bleaching vat having its bottom sloping 60 toward the pump and passageways for the liquors through both the front and rear walls of the bleaching vat near the brim of said bleaching vat.

6. In an apparatus for bleaching and the like the combination of a mixing vat, a

bleaching vat, a pipe system connecting said mixing and said bleaching vats and a pump with connections to said pipe system, said bleaching vat having its bottom sloping toward the pump with a framewise support on 70 said sloping bottom having a rim around the inside opening, a hole in the framewise support and wall to afford communication with the lower horizontal pipe and passageways for the liquors through both the front and 75 rear walls of the bleaching vat near the brim of said bleaching vat.

7. In an apparatus for bleaching and the like a bleaching vat having a sloping bottom, a framewise support provided with a rim carried by said bottom, passageways for the liquors near the top and bottom of the bleaching vat, and a container sliding 80 loosely within and resting on the support above the sloping bottom of said bleaching 85 vat.

8. In an apparatus for bleaching and the like a bleaching vat having a sloping bottom, a framewise support provided with a rim carried by said bottom, passageways for 90 the liquors near the top and bottom of the bleaching vat and a container sliding loosely within and resting on the support above the sloping bottom of the bleaching vat, the side-walls of said container terminating 95 somewhat below the brim of the bleaching vat.

9. In an apparatus for bleaching and the like a bleaching vat having a sloping bottom, a framewise support provided with a rim carried by said bottom, passageways for the liquor near the top and bottom of the bleaching vat, a container sliding loosely within and resting on the support above the sloping bottom of the bleaching vat, the 100 side-walls of said container terminating somewhat below the rim of the bleaching 105 vat and a ledge on the front and rear walls of the container running parallel to and at a distance from the side-wall most remote 110 from the pump.

10. In an apparatus for bleaching and the like a bleaching vat having a sloping bottom, a framewise support provided with a rim carried by said bottom, passageways 115 for the liquors near the top and bottom of the bleaching vat, a container sliding loosely within and resting on the support above the sloping bottom of the bleaching vat having side-walls lower than the rim of the bleaching vat, ledges on the opposite front and rear walls, one side-wall of the container being constructed as a door hinged at the upper short side to be opened by swinging upward, the side-wall opposite to the last 120 named one being also constructed as a door and hinged at either of its long sides to be opened by swinging backward toward the side to which it is hinged.

11. In an apparatus for bleaching and the 130

like a bleaching vat having a sloping bottom, a framelike support provided with a rim carried by said bottom, passageways for the liquors near the top and bottom of the bleaching vat, a container sliding loosely within and resting on the support above the sloping bottom of the bleaching vat, the side-walls of the container terminating somewhat below the brim of the bleaching vat and a plurality of trellises arranged horizontally at a distance from each other

and substantially at right angles to the side-walls of the container.

In testimony whereof we have signed this specification in the presence of two sub- 15 scribing witnesses.
